UNITED STATES PATENT OFFICE.

NATHAN B. NEWCOMER AND CARL O. JOHNSON, OF PAONIA, COLORADO.

ORCHARD-HEATER.

1,038,420.

Specification of Letters Patent. Patented Sept. 10, 1912.

Application filed May 21, 1912. Serial No. 698,746.

To all whom it may concern:

Be it known that we, NATHAN B. NEWCOMER and CARL O. JOHNSON, of Paonia, in the county of Delta and State of Colorado, (each of whose post-office address is Paonia, Colorado,) have invented certain new and useful Improvements in Orchard-Heaters; and we do hereby declare the following to be a full, clear, and exact description of the invention, such as will enable others skilled in the art to which it appertains to make and use the same.

The object of our invention is to provide an improved and efficient heater for orchards, in the use of which uniform radiation of heat is secured in all directions without the creation of much if any smoke, and with the consumption of but a minimum quantity of fuel.

20 In the drawings, Figure 1 is a view in perspective of our invention. Fig. 2 is a vertical sectional view thereof. Fig. 3 is a modification.

Referring to the drawings, 1 designates 25 an open top container or reservoir in which the fuel, preferably crude oil, is burned. This container is shown as circular in cross-section, and is open only at the top. Two ring-like plates 3, 4, of slightly greater diameter than the container, are designed to rest upon the upper edge thereof, and each is formed with a series of vertical openings 5, 5', respectively, these openings together forming a passageway through which air 30 may be drawn into the container. The plate 3 may be moved over the plate 4 for the purpose of regulating the size of these openings and consequently the air inlet.

6 is a radiator which we have shown in 40 the form of an inverted frustum of a cone. Its smaller end fits within the central opening of the plates 3 and 4, by which it is supported. A short distance above its lower end the radiator is formed with a series of 45 circumferential openings 7, while near its top is a second series of circumferential openings 8, these latter being larger than the openings 7. A cover 9 closes the radiator to the atmosphere at the top. This cover

may be removed to increase the draft, and 50 may be employed as a cover for the container when the device is not in use.

The crude oil is placed in the container and lighted, and the radiator being in position, air is drawn into the container through 55 the vertical openings in the supporting ring and into the radiator through the horizontal openings 7. In this way not only is a complete draft secured, but substantially all combustible gases are completely consumed 60 in the radiator, thus preventing smoke and securing thorough and uniform radiation of the heat.

In Fig. 3 we have shown a slight modification, the radiator 6' at its lower end being 65 of approximately the same size as the top of the container 1' upon which it is designed to fit while its upper end is of somewhat smaller diameter. Near its opposite ends the radiator has two series of circumferential openings 7' and 8'. The admission of air through opening 7' may be regulated by a damper 10, in the form of a circular band.

We claim as our invention:

1. In combination with a container, a radiator mounted thereon, one of said members having openings thereto at their meeting ends, a circumferential damper for regulating the passage through said openings, said radiator being closed at its top 75 and having circumferential openings immediately adjacent said top.

2. A portable orchard heater comprising an imperforate fuel container, a radiator, and ring-like plates mounted on said container, and having each a series of vertical openings, said radiator fitting on said rings, and having an upper and lower series of air openings.

In testimony whereof, we have signed this 90 specification in the presence of two subscribing witnesses.

NATHAN B. NEWCOMER.
CARL O. JOHNSON.
